A. D. DALY:
GATE FOR COVERED VEHICLES.
APPLICATION FILED JAN. 7, 1922.

1,427,195.

Patented Aug. 29, 1922.

By William C. Linton.
Attorney

UNITED STATES PATENT OFFICE.

ALVIN DAVID DALY, OF TUCSON, ARIZONA.

GATE FOR COVERED VEHICLES.

1,427,195.

Specification of Letters Patent. Patented Aug. 29, 1922.

Application filed January 7, 1922. Serial No. 527,692.

To all whom it may concern:

Be it known that I, ALVIN DAVID DALY, a citizen of the United States, residing at Tucson, Arizona, have invented certain new and useful Improvements in Gates for Covered Vehicles; and I do hereby declare that the following is a full, clear, concise, and exact description of the same, such as will enable others skilled in the art to which it 5 appertains to make and use the same.

This invention relates to improvements in closures or gates particularly adapted for use in connection with covered vehicle bodies, having for an object to provide a 15 gate which when in closed position, affords a positive and effectual barrier or closure for the rear end of a covered vehicle body, requiring but a minimum amount of space when installed and capable of being moved 20 to an out of the way position when opened, in order that ready access may be had to the body interior.

It is also an object of the invention to provide a gate of the character mentioned 25 adapted to be moved vertically and horizontally to a position in proximity to the vehicle body cover top when opened, and to be releasably retained in such position by means of the novel form of traps employed 30 therefor.

Other objects will be in part obvious and in part pointed out hereinafter.

In order that the invention and its mode of operation may be readily understood by 35 persons skilled in the art, I have in the accompanying illustrative drawings and in the detailed following description based thereon set out one possible embodiment of the same.

40 In these drawings:—

Figure 1 is a vertical longitudinal section through a fragment of a vehicle body cover showing my improved gate positioned in proximity to the way therein, the gate being 45 in a partially open position;

Figure 2 is a detail in perspective of my improved gate; and,

Figure 3 is a fragmentary detail in horizontal section taken through one side of the 50 gate supporting frame and the gate showing the connection between the two.

Having more particular reference to the drawings in connection with which like characters of reference will designate corresponding parts throughout, C indicates a vehicle body cover in its entirety, said cover

having wire grating or drill sides 8, while a gateway or opening is formed in the rear end of the cover for an obvious purpose; posts 1 being arranged upon the opposite 60 sides of said gateway and as will be understood, affording stays or bolsters for the cover C and having channeled iron strips 2 on certain of the sides thereof adapted to receive the adjacent ends of the wires constituting the grating sides 8, as clearly shown in the Figure 3. Upon the inner sides of the several posts 1, vertically disposed U-shaped channeled metal strips 3 are arranged, being secured to adjacent portions 70 of said posts in a suitable manner and having inwardly extending extensions 3' formed thereupon, in proximity to their upper end portions, while openings 4 are also formed in those portions of the channeled strips 3 75 adjacent the connection of their respective branches or extensions 3' with the same, this being clearly shown in the Figure 1. Of course, the extensions 3' are suitably secured to adjacent portions of the cover C to prevent 80 their movement with relation to the latter.

The door, forming a part of this invention, may be stated to comprise a substantially rectangular frame 5 formed of channeled metal and having oppositely disposed spaced pivot pins 6 and 7 arranged in the base portions of the channeled metal constituting the opposite sides of the same, said pins 6 and 7, as will be noted, upon reference 85 to the Figures 1 and 2, being arranged in proximity to the top and bottom portions of the frame 5. Wire grating 8 may be and preferably is arranged in the frame 5 thus completing the gate, although in this connection, it is of course to be understood that any suitable form of body or panelling may be substituted in lieu of this grating, such 90 as conditions or preference may dictate.

When mounting the gate in the channeled strips 3 with their extensions 3', the lower pivot pins 7 upon the opposite sides of the frame are engaged in the vertically disposed portions of said strips, that is, those portions indicated by the numerals 3; rubber stops 9 being arranged in the lower ends of said strips and affording means for limiting downward movement of the pivot pins 7 and likewise to prevent undue or material vibration of the gate when in 105 closed position. The uppermost pivot pins 6 are engaged in the channeled strips pre- 110

sented by the inwardly disposed extensions 3', as shown in the Figure 1, and when the gate is moved to its full closed position, said pins 6 will have entered the vertically dis-
5 posed strips 3, as shown in the dotted lines in the Figure 1, thus completely closing the way formed in the rear end of the cover C. At this time, the lower pivot pins 7 will be engaged with or arranged directly adjacent
10 to the rubber cushioning stops 9, as is also shown in dotted lines in the Figure 1. In order that the gate will be releasably held in its closed position, I may and preferably do employ a contractile coiled spring 10,
15 connecting one end to one side of the frame 5, while the opposite end thereof is suitably engaged with the grating of one of the sides s. Thus, when the gate is moved to its fully closed position, the contractile spring 10
20 will be extended and by consequence, the tension under which it will be placed serves to apply sufficient pressure to the gate for preventing its material vibration. Likewise, when the gate is moved to its fully
25 open position as shown in dotted lines in Figure 1, the spring 10 will be also extended as shown in dotted lines and by exerting a downward pull upon the innermost end of the gate frame 5, will prevent material
30 movement of the same in the channelled strip extensions 3'.

When it is desired to move the gate to an open position with respect to the cover C, the lower portion of the same is engaged
35 and moved upwardly. At the same time, with slight upward movement of the gate, an inward pull will be imparted thereto by reason of the extended coil spring 10, thus
40 the oppositely disposed pivot pins 6 will be moved inwardly through the extension strips 3', to the position shown in full lines in Figure 1. At this time, the lower portion of the gate may be manually swung upwardly, the pivot pins 7 passing through
45 the strips 3, while the upper end of the same will move inwardly through or over the extensions 3', because of the engagement of the pivot pins 6 therein. The lower portion of the gate is moved to its extreme up-
50 permost position with respect to the strips 3, whereupon the pivot pins 7 will be brought to positions adjacent the openings 4 in the side walls of the upper portions of said strips 3. At this time, an inward thrust
55 is imparted to the gate moving the pivot

pins 7 through said openings 4 to the position shown in dotted lines in Figure 1, that is, in the seats provided for the same by the arrangement of the openings 4 at points slightly above the connection of the inwardly disposed extensions 3' with the vertically disposed channelled strips 3. As hereinbefore stated, when the gate is in its open position, the spring 10 will be again distended and by reason of its tension, will tend to pull the inner portion of the gate downwardly and by consequence, retain the outer portion thereof with the pivot pins 7 in their lower-most positions upon the upper sides of the extension strips 3', preventing said pivot pins from passing through the openings 4 and permitting the gate to accidentally or unduly close.

Manifestly, the construction shown is capable of considerable modification and such modification as is within the scope of my claim, I consider within the spirit of my invention.

I claim:

The combination with a vehicle body cover having a way therein, posts upon the opposite sides of said way, a gate for said way, of vertical channelled strips secured to the inner sides of said posts, substantially horizontally extending channelled strips 85 formed integral with and communicating with the upper portions of said vertical strips, said vertical strips each having an opening therein at points slightly above the connection to the horizontal strips, oppositely disposed pivot pins arranged on the upper and lower ends of the several sides of said gate and adapted to be received in the channels of said vertical and longitudinal strips, rubber stops closing the lower 90 ends of the channels of said vertical strips and adapted to retain said gate in a vertical position within the vehicle body cover way, the pivot pins upon the lower end of said gate being adapted to be inserted within the 100 openings in the vertical strips and rest upon the upper walls of the horizontal strips for retaining the gate in its open position, a coil spring connected to said gate and adapted to apply pressure thereto when the gate is 105 in its open or closed position, substantially as and for the purpose specified.

In witness whereof I have hereunto set my hand.

ALVIN DAVID DALY.
